CAN FEEDING DEVICE

John Albertoli, San Francisco, Calif.

Original application December 3, 1945, Serial No. 632,476. Divided and this application March 7, 1949, Serial No. 80,064

6 Claims. (Cl. 198—26)

1

This invention relates to a can feeding device and is a division of my application Serial No. 632,476 filed December 3, 1945.

One of the objects of the invention is the provision of a can feeding device that is adapted to control the delivery of cans to a filling station, or to any other desired point more efficiently than heretofore.

It is customary in canneries and packing plants to convey cans on their sides, and in side by side relationship along a generally horizontally extending path of travel, and to withdraw cans from such path by gravity at certain spaced points therealong for conducting the cans so withdrawn to various stations or places where the cans may be filled, labelled or otherwise handled. My United States Letters Patent 1,802,546 of April 28, 1931 is an example of one such system.

One of the difficulties in systems of the above character is the jamming of cans where they are withdrawn from the main supply conveyor or from generally horizontally extending path.

One of the objects of this invention is the provision of a device that overcomes the above objections, and that is simple and reliable.

A still further object of the invention is the provision of a can feeding device that is adapted to be actuated by the weight of a predetermined number of cans in the delivery chute from the main conveyor, and at a point relatively close to said main conveyor.

An additional object of the invention is the provision of a can feeding device that includes means for facilitating the movement of the cans from the main supply conveyor through a chute or chute leading to a point remote from said supply conveyor.

Another object of the invention is the provision of a can feeding device including a provision for making an identifying imprint such as a number or symbol on the cans as they pass along the delivery chute on the way to the filler or to such other device as may be desired.

Other objects and advantages will appear in the description and in the drawings.

In the drawings,

Fig. 1 is a diagrammatic side view showing a portion of a main supply conveyor and several feed devices leading downwardly therefrom.

Fig. 2 is a part sectional, part elevational view of a feed device for feeding cans to a station, and which device includes a printer.

Fig. 3 is an elevational view of the device of

2

Fig. 2 as seen at right angles to the latter from the right hand side of Fig. 2 and with the spacer at the bottom shown partly in section.

In detail, the cans that are being handled are 5 designated 2, and are shown as being supported on their sides on a carrier 50. They are moved along said carrier or conveyor by a power driven endless hold-down belt 51. This carrier comprises a track, and is formed with a gap, as seen 10 in Fig. 2, for dropping the cans through said gap from said carrier into the upper end of a generally vertically downwardly extending feed chute or device.

This feed device into which the cans are 15 dropped, comprises a pair of spaced opposed vertical side plates 52, 53 that form two of the opposite sides of the chute.

A horizontal roller 54 extends between plates 20 52, 53 adjacent the delivery edge of carrier 50 over which oncoming cans on said carrier are adapted to fall into the chute, and over which the cans are carried. This roller is supported at its ends for rotation by plates 52, 53.

A star wheel 55 below roller 54 is disposed in 25 a vertical plane for rotation about the axis of horizontal shaft 57, and which shaft may be journaled at its ends in plates 52, 53. Wheel 55, as shown, has four equally spaced spokes. Inasmuch as shaft 57 is substantially directly below the roller 54, the spokes at one side of the star wheel will project into the chute, and said spokes are so arranged that the first can dropping over roller 54 will drop onto one of said spokes when such spoke is substantially horizontal and will cause a quarter turn of the star 30 wheel to bring another spoke into the path of the next can.

A spring 58 and a friction collar 59 function 35 to frictionally stop the star wheel after each quarter revolution thereof so that its momentum will not cause movement of the wheel after each can has caused the quarter turn thereof. As soon as the weight of the falling can is off the wheel the movement of the wheel will stop.

Spacers 60 extending between plates 52, 53 40 function to space the said plates apart and to also guide the cans in their movement past the star wheel, or to function as the side of the chute opposite the star wheel.

It is pertinent to note that the can that is directly on the laterally projecting arm of the star wheel together with the weight of the can thereabove that is in alignment with the cans on the carrier 50, is sufficient in itself to cause the star 45 wheel to rotate a quarter turn, provided the star

55

wheel is not held from turning. Thus no reliance is placed upon a long row of cans to cause movement of the star wheel, nor is the star wheel positively rotated by any outside agency. The desirability of this arrangement will be more clearly brought out later on.

As the cans move past the star wheel, (assuming the latter is not positively held, but is free to rotate) they will pass downwardly between the concave face of an arcuately shaped plate 61 that is at the same side of the chute as the star wheel, and a printing wheel 62 that carries printing type 63 on its peripheral surface. This printing wheel is conventional and is carried on a shaft 64 that is journalled at its ends in plates 52, 53. A pulley 65 and belt 66 driven from any suitable source of power may rotate the printing wheel in the direction of the arrow (Fig. 2), that is on the pulley 65. This rotation of the printing wheel will also facilitate movement of the cans past plate 61. Disks 67 secured on shaft 64 may also engage the cans as they are moved past the printing wheel to hold them horizontal during said movement, but said disks are not of sufficient diameter to prevent printing by the printing wheel.

The plate 61 is supported at its upper and lower ends on horizontal rods 70 that extend through enlarged openings 68 in sides 52, 53. Springs 71 are secured at one of their ends to the outwardly projecting ends of rods 70 and the other ends of said springs are secured to lugs 72 on plate 52 (Fig. 3). There is a pair of similar springs at opposite ends of said rods, but only one set is shown inasmuch as the other set is concealed within box 73 that houses a conventional mechanism for shifting the printer 62.

The printer is ordinarily used for printing on the cans any desired symbol for designating the grade of fruit in the cans or to be placed in them.

The cans that pass the printer are adapted to move downwardly by gravity onto a projection 75 that is at the bottom end of a vertically extending lever 76. Lever 76 is pivoted at 77 for swinging of its lower end inwardly and slightly upwardly and the upper end of said lever has a lateral projection 78 that is adapted to engage one of the arms 56 of the star wheel when said lower end is so swung. A spacer and tie rod combination 79 between plate 61 and said portion 75 prevent cans from contacting lever 76. A spring 100 (Fig. 3) connects the lower end of lever 76 below pivot 77 with wall 52 so as to swing the lever laterally for releasing the star wheel unless a can is on the portion 75.

Cans engaging the portion 75 will also be engaged by rotating disks 80 that will withdraw the cans from the portion 75, by frictional engagement with said cans, and onto the continuation 81 of the chute that leads to the station, provided there are no cans on said continuation that would block the movement of the can past said disks. The disks 80 are on a shaft 82 that carries a pulley 83 and which pulley, in turn, is driven by a belt 84 from any suitable source of power.

The star wheel 55 is so positioned that one of its arms will be locked in a position extending horizontally into the chute when a can is against the portion 75 of the lever 76, and when a can such as is indicated at 90 in Fig. 2, is supported on arm 56 of the star wheel, the cans 2 of the main supply carrier will be moved across can 90 and onto the continuation of said carrier at the side opposite roller 54.

When a can such as can 91, is supported on

portion 75, it is obvious that the can 90 will be held in the upper open end of the chute on the horizontal arm of the star wheel. However, as soon as can 91 is permitted to be moved off the portion 75 by disks 80 and by reason of withdrawal of a can from continuation 81 of the chute, the lower end of lever 76 is free to swing generally toward disks 80 and the projection 78 will free the star wheel for dropping the can supported thereon to the printer for movement therewith onto portion 75.

It is obvious that the printer 62 also facilitates downward movement of the cans in the chute between sides 52, 53, the latter being rotated in the direction indicated by the arrows on pulley 65 (Fig. 2).

While the disks 80 function to draw can 91 out of the chute thereabove and onto continuation 81, the weight of can 90 at the star wheel is sufficient to actuate the star wheel when the star wheel is free to rotate. Thus can 90 engages the horizontal arm of the star wheel near the outer end of the latter so as to insure operation of said wheel. The weight of the can above can 90, and in the so called "supply row" obviously is added to the weight of can 90 when the supply row is filled, which it will be in normal operation.

In the event the continuation 81 at the lower end of the vertical chute is filled with cans, the disks 80 will merely slide on can 91 without moving the latter, thus a force is being constantly exerted on can 91, which is transmitted to the cans on continuation 81, tending to move can 91 off the portion 75.

There may be several similar portions 75 at the lower end of lever 76 to engage the lower side of a can at several spaced points, although one will function satisfactorily in most cases. Also the upper edges of the portion 75 may be curved more steeply, if desired, so that two cans may be in engagement with the disks 80 at the same time. Other modifications within the scope of the invention may obviously be made inasmuch as the drawings are not intended to be restrictive of the invention, but are merely illustrations of a preferred form.

One of the important details is the structure whereby the star wheel is adjacent the inlet to the chute and is released for actuation by reason of the absence of a can on portion 75 instead of the application of force in the withdrawal of a can. The feed to and from the chute is automatic. The star wheel at the upper end of the chute is positively held locked by a can 91 at the lower end, and can 91 is being constantly power-urged out of the chute so unless there are cans ahead of can 91 that prevents it from being moved past disks 80, the cans will constantly be moved out of the chute and the chute will be filled. However, the top can in the chute that closes the same is not supported in closing position by a relatively long row of cans in the chute, with the possible jamming of the cans in the chute from the weight thereon. Instead the top can is held by the star wheel free of the cans therebelow, and the cans between the member 75 and the star wheel are free of the weight and force of the cans above the star wheel. By reason of this arrangement, the possibility of the cans becoming jammed in the chute is practically eliminated.

I claim:

1. A can feeding device comprising a generally vertically extending chute for passing cans in a single file downwardly therethrough, said chute being open at its upper end for receiving cans

therein, an upper support within said chute for supporting a can within said upper open end, a lower support spaced below said upper support for supporting a can thereon in a position closing said chute, said upper support being movable under the influence of the weight of the can adapted to be supported thereon to a position releasing such latter can for downward movement in said chute to said lower support, said lower support being supported for movement automatically to a position blocking movement of cans in said chute therewith upon absence of a can on said lower support and means for so moving said lower support, a stop member releasably holding said upper support in a position for supporting a can in said upper end of said chute and movable to a position releasing said upper support for movement to said position for releasing said last mentioned can, and means connecting said lower support with said stop member for moving said stop member to a position releasing said upper support upon said absence of a can on said lower support and consequent movement of said lower support to can blocking position.

2. A can feeding device comprising a generally vertically extending chute for passing cans in a single file downwardly therethrough, said chute being open at its upper end for receiving cans therein, an upper support within said chute for supporting a can within said upper open end, a lower support spaced below said upper support for supporting a can thereon in a position closing said chute, said upper support being movable under the influence of the weight of the can adapted to be supported thereon to a position releasing such latter can for downward movement in said chute to said lower support, said lower support being supported for movement automatically to a position blocking movement of cans in said chute therewith upon absence of a can on said lower support and means for so moving said lower support, a stop member releasably holding said upper support in a position for supporting a can in said upper end of said chute and movable to a position releasing said upper support for movement to said position for releasing said last mentioned can, and means connecting said lower support with said stop member for moving said stop member to a position releasing said upper support upon said absence of a can on said lower support and consequent movement of said lower support to can blocking position, a can moving mechanism at one side of said lower support including a power driven rotary element engageable with a can on said support for movement of such can past the latter and out of said chute.

3. A can feeding device comprising a generally vertically extending chute for passing cans in a single file downwardly therethrough, said chute being open at its upper end for receiving cans therein, an upper support within said chute for supporting a can within said upper open end, a lower support spaced below said upper support for supporting a can thereon in a position closing said chute, said upper support being movable under the influence of the weight of the can adapted to be supported thereon to a position releasing such latter can for downward movement in said chute to said lower support, said lower support being supported for movement automatically to a position blocking movement of cans in said chute therewith upon absence of a can on said lower support and means for so moving said lower support, a stop member releasably holding said upper support in a position for sup-

porting a can in said upper end of said chute and movable to a position releasing said upper support for movement to said position for releasing said last mentioned can, and means connecting said lower support with said stop member for causing the latter to so move upon said absence of a can on said lower support and consequent movement of said lower support to can blocking position, a can moving mechanism at one side of said lower support for movement of cans past the latter and out of said chute, said mechanism including a rotatable wheel having a relatively smooth peripheral surface adapted to frictionally engage cans that are on said lower support for causing said movement of said cans, said surface being adapted to slide on cans engaged thereby without moving the latter in the event the preceding can moved by said wheel off said member is in a position obstructing said movement of the next can on said member.

4. In a can feeding device, an open ended vertically extending chute for downward passage of cans in a single file therethrough, a star wheel having equally spaced arms and rotatably supported adjacent the upper end of said chute for rotation of its arms about a horizontal axis successively to a position projecting into said chute for supporting a can in said upper end and for releasing the can so supported upon fractional rotation of said wheel to position the next succeeding arm thereof in said position, a vertically extending lever adjacent one side of said chute, a member on the lower end of said lever projecting into the path of travel of cans adapted to pass downwardly through said chute, a rotary can engaging mechanism opposite said member, an arm engaging element on the upper end of said lever adapted to disengage the arms of said wheel upon movement of said member toward said mechanism when the space between said member and said mechanism is clear of a can, a pivot supporting said lever for swinging said element to arm holding position upon a can being in a position between said mechanism and said member, said mechanism being adapted to move cans in said chute past said member for so swinging the latter.

5. In a can feeding device, an open ended vertically extending chute for downward passage of cans in a single file therethrough, a star wheel having equally spaced arms and rotatably supported adjacent the upper end of said chute for rotation of its arms about a horizontal axis successively to a position projecting into said chute for supporting a can in said upper end and for releasing the can so supported upon fractional rotation of said wheel to position the next succeeding arm thereof in said position, a vertically extending lever adjacent one side of said chute, a member on the lower end of said lever projecting into the path of travel of cans adapted to pass downwardly through said chute, a rotary can engaging mechanism opposite said member, an arm engaging element on the upper end of said lever adapted to disengage the arms of said wheel upon movement of said member toward said mechanism when the space between said member and said mechanism is clear of a can, a pivot supporting said lever for swinging said element to arm holding position upon a can being in a position between said mechanism and said member, said mechanism including a circular wheel rotatable about a horizontal axis with its periphery adapted to engage cans that are in contact

with said member for moving such cans past said member, and means for rotating said wheel.

6. In a can distributing system having a horizontally extending track for longitudinal horizontal movement of a row of cans thereon and provided with a gap for dropping individual cans therethrough; a vertically extending chute having an open upper end for positioning at said gap for receiving said individual cans, a star wheel supported on said chute for rotation about a horizontal axis with an arm thereof at one of its sides extending across said chute for supporting a single can thereon below said row, said star wheel being rotatable under the influence of gravity of the cans over said arm to pass the can on said arm downwardly into said chute and to interpose the next arm on the wheel across said chute in can supporting position, a vertically extending lever, a pivot on said chute supporting said lever at a point spaced between its ends for swinging 15 about the horizontal axis of said pivot, a projection on the lower end of said lever positioned for supporting the lower can in said chute thereon

and swingable about said pivot outwardly of said chute under the influence of said lower can for thereby swinging the upper end of said lever inwardly relative to said chute, a stop member on the upper end of said lever engageable with said wheel when said projection and lower end of said lever is swung outwardly for holding said wheel stationary with said single can thereon, and the lower end of said lever and said projection being swingable inwardly when said projection is free from a can thereon for swinging of the upper end of said lever and said stop member out of holding position.
